IRONING MACHINE

Patrick A. Bayless, Minneapolis, Minn.

Application March 20, 1930, Serial No. 437,399

15 Claims. (Cl. 68—9)

This invention relates generally to improvements in laundry machines and particularly relates to improvements in flat work ironing machines. Among the objects of the invention are: 5 to provide the maximum of ironing surface, in a machine of minimum size; to eliminate ironing rolls and therefore eliminate gearing which operates these rolls; to provide more ventilation for the padding; to avoid the use of strings for holding the goods in flat condition as it passes through the ironer; to provide means whereby padding can be moved away from the steam chest when the machine is not in use; and to eliminate noise, as result of substantial reduction in 10 amount of transmission, gearing, etc.

In the principal makes of machines of this class, the working surface of the steam chest is provided with depressions with which the padded rolls cooperate. The radius of curvature of the 20 depressions is greater than that of the radius of the rolls so that there is a substantial reduction in the area of contact between the roll or rolls, and the steam chest. In the present device, one hundred per cent contact is obtained between the 25 padding, goods, and steam chest.

A feature of the invention includes ventilating means for the padding whereby it is not burned, this means includes perforated slat-like structures as backing for the padding. Another feature is the use of slats which, in their movement 30 around sprocket wheels, act to "work" the padding and keep it soft. This hardening is due to continuous rolling pressures without sufficient ventilation. In other devices, the padding has 35 to be frequently removed and fluffed up by tumbling machines. The hardening of padding conditions it for burning. In the present device, hardening and burning are substantially eliminated.

The present device is practically noiseless because no pressing rolls are used, and the roll 40 gearing, and bearings therefor which were arranged so that compensation for expansion and contraction could take place, are, of course, no longer necessary. The present device provides 45 means for insulating the steam chest so that the heat transmission to the frame is practically eliminated.

Features of the invention include, along with 50 the broader ideas of means, all the details of construction.

Advantages will be set forth in the description of the drawings forming a part of this application, and in said drawings.

55 Figure 1 is a side elevation of one embodiment

of the invention with parts broken away to show portions of the interior structure;

Figure 2 is a plan view corresponding to Figure 1 with parts broken away;

Figure 3 is a substantially central vertical longitudinal section;

Figure 4 is a transverse section substantially on line 4—4 of Figure 1 illustrating the details of the driving mechanism;

Figure 5 is a vertical section on line 5—5 of Figure 1 illustrating the arrangement of the ironing means adjusting mechanism;

Figure 6 is a vertical section on line 6—6 of Figure 1 illustrating a portion of the adjusting mechanism for the delivery apron, (as distinguished from the ironing aprons); and

Figure 7 is a plan section taken approximately on line 7—7 of Figure 5, further illustrating the arrangement of the driving and apron adjusting mechanisms.

The machine includes two side frame members, see Figure 4, respectively generally indicated 1 and 2, and these frames are suitably cross-connected by upper and lower series of tie and truss members respectively designated 3—4. 25 Mounted between these frames and providing upper and lower plane surfaces, is a steam chest 7 suitably secured as by bolting to brackets 8. Interposed between the brackets 8 and the extension 9 of the chest is non-heat conducting material 10, the function of which is to reduce to the minimum heat conduction from the steam chest to the frame. The upper and lower horizontal surfaces of the steam chest, see Figure 3, are respectively indicated 12—13. At one end of 30 the chest these surfaces merge into a curved portion 15, whereby goods to be ironed may be continuously fed along the upper surface 12, then around the curved end surface and downwardly and against the lower surface 13. The feed and 35 ironing pressure is obtained by endless flat surfaced padded belt-like means, or aprons, later to be described. At the opposite end of the steam chest, the bottom surface 13 is curved as at 16 to direct the goods downwardly around the lower 40 ironing apron. The curved portion 16 is concentric with the axis of shaft 53 of the lower ironing apron. A suitable drain opening 17 is also provided for the steam chest and the steam is introduced at one end at 19 and is discharged 45 at the opposite end at 18. It is assumed that steam supply means is provided, although not actually shown.

One of the main features of this invention is the use of an endless apron-like padded ironing 55

element for moving the goods along the face of the steam chest. Another feature is the use of two such elements arranged to move the goods along one face of the chest in one direction and then continue motion of the goods along the opposite face of the chest in an opposite direction, so the goods is substantially maintained in flat condition throughout the ironing period. After the goods has been ironed, it is received by an endless apron, herein called the delivery apron to distinguish it from the "ironing" aprons above referred to. The goods is, by means of this apron, ejected from the machine during travel in the same direction in which it entered the machine, and this discharge, therefore, takes place at that end of the machine opposite the point at which it was introduced into the machine.

By the use of the belt-like pad-carrying elements, a plane surface feed is provided in a straight line, and as the result, there are no pleats or corner turnovers, heretofore caused by the goods hitting rolls or cylinders. The provision of a straight line feed over plane surfaces makes for easy spreading and straightening of the goods. The pressure is applied evenly over the entire surface of the steam chest during ironing, and there is no part of the goods which is not under pressure during the ironing operation, and constantly under pressure. The goods are, therefore, ironed dry, instead of being partly ironed dry and partly dried by exposure to the atmosphere, as when they pass from one roller to the next in the cylinder type of machine.

Another advantage is that the same kind of contact is obtained at the under surface of the steam as at the upper. Before describing the endless belt-like padded elements which perform the ironing operation and move the goods, it is to be noted, see Figure 3, that both upper and lower surfaces of the steam chest are used, and that the goods has substantially a continuous contact throughout a very much more extended ironing period. Another advantage is that but one delivery apron is needed, as against two required in cylinder or roll type machines.

Referring to Figures 3 and 4: The movable pressing element has the form of a frame-supported endless belt or apron including four sprocket chains 20 driven by sprocket wheels 21 mounted on shafts 22-23 arranged above the steam chest, one at each opposite end. Shaft 22 is driven in a manner to be described. The body of the apron or working portion is formed by slat-like elements 32, formed to obtain the desired stiffness, and in this instance having the form of channels which cross-connect the chains 23. Each channel element 32 has a terminal turned portion 23 which forms one of the links of the chain, the usual pivots 24 being used. The slat-like channel elements are perforated as at 25, see Figure 2, to provide for pad ventilation, and may be spaced apart as at 26 to increase ventilating ability. The spaces are somewhat exaggerated in the drawings and preferably will not be as proportionately great as there shown. Moreover, air may pass laterally and horizontally between the runs of the endless pad-carrying element so that ample ventilation, to prevent over-heating, is provided for. One of the channel-like elements, see Figure 3 designated 27 is formed to provide a pocket 28 in which one end of an endless pad 29 is arranged as shown. The pad terminal is secured by means of a series of suitable fastening devices 30 spaced lengthwise of the channel 27, and passing through a suitable pressure-apply-

ing strip 31. The opposite end of the endless pad is arranged on top of the strip 30 and is secured by cementing or otherwise appropriately fastened, so that a smooth continuous surface is provided across the joint. This padding may be of any of the usual types used in this art. The use of a single endless pad is a feature of this invention.

Certain elements of the links of the intermediate chains 23 have extensions 33 which are attached to the channel elements 32. Shafts 22-23 are each mounted (see Figure 4) in suitable bearing blocks 34 adapted to slide vertically in ways 35 of the frame members 1 and 2. The bearing blocks 34 are suitably connected to channel irons 36 which form part of the frame structure of the ironing apron. By the use of the sliding blocks, the ironing apron and its supporting structure can be bodily adjusted with reference to the ironing surface 12 of the steam chest 1, so that the pressure can be varied as well as the distances between these surfaces, according to the character of the goods being ironed. Other blocks or nuts also arranged in vertical guides form part of the apron adjusting mechanism, later to be described.

In order that the padding be maintained in strictly flat condition during the ironing operation, and in substantial parallelism with the working face 12 of the chest, tracks are provided against which the links of the chain ride (see Figures 3 and 5). These tracks 40 are four in number, corresponding to the number of chains. The tracks are in the form of straight-edged plates, and each has a series of elongated ventilating openings 41. Thus, the structure which forms a carrier for the ironing pad is an open structure permitting the maximum of free circulation of air at opposite face sides of both runs of the pad, and thus substantially preventing burning of the padding, or conditioning of it to be burned. The channels 36 are cross-connected by means of bars or tie rods 43, which rods support chain tracks 40.

The lower ironing apron 42 has substantially the same construction as the upper, and its upper run cooperates with the under surface of the steam chest, to perform the ironing operation.

The lower ironer (see Figures 3 and 4) is operated by sprockets 58-59 carried by shafts 52-53. The slat-like channel elements are indicated at 54, and the chains at 55. Referring to Figure 3, it will be noted that the shaft 52 is at a level above shaft 53 to bring the upper run of the carrier upwardly to a position to receive the goods from the upper ironing apron and guide it around the curved portion 15 of the chest and downwardly into the upper run of the lower ironing means. The frame members of the lower ironer are indicated at 56, and shafts 52-53 are of course journaled in these channel elements 56. The shaft 53, see Figure 4, passes through journal blocks 58 (corresponding to journal blocks 34) and these blocks are adapted to move vertically in guides 59. The shaft 52 (see Figure 3) is not journaled in blocks similar to block 58 but is only journaled in the frame members 56. The lower ironing element can be bodily adjusted in exactly the same manner as the upper ironer, in a direction toward and away from the working surface of the chest.

The padding for the lower carrier is indicated at 61. It is an endless element and is connected in exactly the same way as the upper padding, the connection being generally indicated at 62. The ventilating structure for the lower ironer is sub-

stantially exactly the same as for the upper, and the leveling elements, or chain tracks, 63, see Figure 5, are also provided and these elements have the series of ventilating openings 64, permitting horizontal ventilation between the runs of the apron. Tie rods 66, see Figures 3 and 5, cross-connect elements 56 and support the level tracks 63.

The curved surface 16 directs the goods downwardly toward the delivery apron now to be described. Before describing the apron structure, it is to be noted that only a single apron is required because of the nature of the present invention. Heretofore, it has been necessary to deliver the goods between two delivery aprons, but by the use of this invention, the lower run of the lower ironing means takes the place of the run of one of the aprons and the upper run of a single apron cooperates with this lower run to feed the goods to point of ejection after ironing. The apron structure is best shown in Figures 3 and 5, and includes two side frames indicated at 67, see Figure 5, suitably cross-connected and trussed as at 68, see Figure 3. Mounted between these frames are rollers respectively designated 69, 70, 71, 72 and 73 which support an endless belt 74 having its upper run adapted to engage and cooperate with the lower run of the lower ironing element to feed the goods, after ironing, to point of ejection from the machine.

It is one of the valuable features of this invention that the ironers, that is the two endless apron-like elements which perform the ironing operation, can be bodily micrometrically adjusted with reference to the surfaces of the steam chest and can be withdrawn from these surfaces a substantial distance when the machine is not in use, to prevent over-heating of the padding. The adjustment of only two ironing elements is here necessary, as distinguished from the separate adjustment of each of a plurality of rolls; heretofore necessary. Moreover, the adjustment of one delivery apron only is necessary herein, while in the old types of flat-work ironers at least two delivery aprons had to be used, and adjusted. Before showing how the various elements of the machine are driven, the structure by which the elements can be adjusted will be first described, along with the structure by which the delivery apron is supported. Referring first to Figure 5, which is a vertical section on line 5-5 of Figure 1: Blocks 82 are attached to the channel elements 36 of the upper ironing apron support. These blocks or nuts are in threaded engagement with vertically arranged shafts 83, rotatably, but non-translatable, mounted in suitable bearings of the side frames 1 and 2. There are pairs of shafts 83, a pair on each side frame, and these shafts are also in threaded engagement with nuts or blocks 84 carried by angle irons 56 corresponding to the lower ironing apron support. Thus, the frames for the upper and lower ironing aprons are capable of vertical adjustment by means of the screws. The blocks or nuts 82-84 are vertically guided as at 90-91.

The threads of the shafts 83 are so arranged as to move the ironing aprons either toward or away from one another and to maintain the padding surfaces in parallel relation with the corresponding working surfaces of the steam chest. The pressure may be varied at will and moreover less pressure applied according to the character of the goods. It is to be noted that proper pressure means better finish of the goods.

By the practice of this invention, the proper spacings and pressures can be quickly and accurately varied.

Referring to Figure 5: The delivery apron 74, which is mounted upon the frame elements 67, is supported by means of stub shafts 97, four in number, in threaded engagement with blocks 98 carried by the frames 67. The shafts are rotatably but non-translatable supported in suitable hanger frames generally indicated at 99 and 100 including vertical extensions which connect with the channel irons 56 of the supporting frame for the lower ironing apron. The frames 99 are preferably connected together by means not herein shown, such as crossed truss rods. The rotation of the threaded shafts 97 by appropriate mechanism now to be described gives a vertical micrometric adjustment of the feed apron with respect to the ironing apron. The upper surface of the upper run of the delivery apron, 20 and the lower surface of the pad of the lower run of the ironing apron are, of course, maintained in strict parallelism for all adjusted positions.

Shafts 97 are simultaneously rotated, and, of course, the pitch and direction of the threads is such as to always move the apron so that an even pressure can be maintained throughout the entire surface of its upper run. Referring to Figure 6, and to Figure 7 which is a 30 plan section on line 7-7 of Figure 5: the lower ends of two of the shafts 97 are provided with worm gears 105, while the lower ends of the other two shafts are provided with bevel gears 106. The worm gears 105 mesh with corresponding worm gears 107 of operating shaft 109 provided with operating handle 110. This shaft is suitably journaled in bearings provided by the frame of which elements 97 are a part. Shaft 109 carries bevel gears 112, meshing with 40 bevel gears 113 carried by cross shafts 114 having at the opposite ends bevel gears 115 meshing with corresponding bevel gears 106. By rotation of shaft 109, all screw shafts 97 will be simultaneously rotated to correspondingly vertically adjust the delivery apron. The delivery apron and its support move in unison with the support for the lower ironing apron, and therefore, when the ironing apron is lowered the delivery apron is lowered. However, the delivery 50 apron can be easily and quickly adjusted independently of the ironing apron.

Referring to Figures 4 and 7: The main drive shaft for the machine is shown at 120 and is provided with a suitable power pulley 121. The 55 shaft 120 is suitably journaled in the side frames 1 and 2, and has keyed thereto two bevel gears 122 meshing with corresponding bevel gears 123 of vertical shafts 124. These vertical shafts are journaled in the bracket bearing blocks 34, and 60 58 which slide in the vertical ways 35-59, which bearing blocks also carry the shaft 22. Carried by each bracket is a gear 125 suitably held by the bracket for rotation but against translation by 65 means not herein shown. These gears are splined to the shafts 124 as at 126. Meshing with the gears 125 are corresponding gears 128 of shaft 22. The bearing blocks 58 of the lower ironing apron have corresponding bevel gears 130 connected for rotation but not for translation by means not shown, and these gears are also splined to the shafts 124 as at 131. Meshing with the gears 130 are bevel gears 132 carried by one shaft 53. It is evident that ironing apron drive 75

can be maintained for all adjusted positions of both aprons.

Power shaft 120 also furnishes power for operating the threaded shafts 83 to raise and lower the ironing means supporting frames. Referring to Figure 5, it will be seen that whenever the shafts 83 are rotated, the ironing apron supporting frames will be moved in unison, either in a direction away from one another and the steam chest, or toward one another and toward the steam chest, and the delivery apron will follow the motion of the lower ironing apron.

In order to utilize the power through shaft 120 to operate the apron raising and lowering means, it is necessary that a clutch be used which is normally unclutched, in other words which will idle during the operation of the machine and at all times except when adjustment is necessary. Referring to Figure 7: Clutch supporting frame 135 is attached to the side frame 1. In this frame is journaled a shaft 139 (shown in dotted lines in Figure 1) and to this shaft is attached a sprocket 137, see Figure 7, connected by a suitable chain 138 with a sprocket 139 of the shaft 120. Journaled in the bracket 135 and in the frame 1, is another shaft 140 having keyed thereto bevel gears 142 meshing with corresponding bevel gears 143 carried by cross shafts 144, also see Figure 5. Cross shafts 144 are provided with bevel gears 146 meshing with corresponding bevel gears 147 of the vertical screw shafts 83. Referring now to Figure 7, shaft 140 has a clutch member 150 splined thereto, and this member is alternately clutchable with gears 151-152 loosely rotative upon shaft 140, and in mesh with the gear 153.

The clutch operates in the usual manner when thrown in clutch with gear 151 the shaft 140 is rotated in one direction and when thrown in clutch with gear 152, the same shaft is rotated in an opposite direction and the rotation of screw shafts 83 correspondingly reversed. The clutch is operated by a lever in turn operated by hand rod which is terminated by knob arranged adjacent the lever 110 at the receiving end of the machine.

Referring now to Figures 2 and 3: The goods are initially fed into the machine over a series of belts 168 operating on suitable rollers carried by shafts 161-162, the shafts being driven in a manner to be described. The goods carried by the belts 168 is carried beneath a feed roll 164 mounted on a suitable shaft 165 driven in a manner to be described. It will be noted at this point that the goods is fed in a straight line to the top surface of the steam chest and straight away to a point between this top surface and the lower surface of the padding of the ironing apron. This straight line feed eliminates pleats and corner turn-overs, which were originally caused by the goods hitting a roll or cylinder. Another point is that no strings are required to hold the goods at any time, and thus the marking of the work by the strings is avoided. The drive for the preliminary feed mechanism including shafts 162-165 is as follows: Referring to Figures 2 and 4, a sprocket wheel 166 is provided on shaft 22, and a chain 167 connects this wheel with the corresponding wheel 168 on the roll shaft 165. A bevel gear 169 is rotatably, but non-translatably, mounted upon a bracket of side frame 1, as shown, and this gear is keyed as at 171 to shaft 124. Now referring to Figure 1: This gear meshes with the corresponding gear 172 of a horizontal shaft 173, suitably jour-

naled at the outer side of frame 1. The opposite end of this shaft 173 has a bevel gear 174 in mesh with the corresponding bevel gear 175 of the shaft 162. In this way the initial feed belts and roll are properly driven to feed the goods between the lower surface of the pad of the ironing apron and the upper surface of the steam chest.

The straight feed is a valuable feature, because by the time the work has reached the end of the steam chest and engages the lower pad-carrying belt, it has been polished or finished or ironed, and is stiff and dry and, therefore, no fold-over can take place.

In the old devices, two aprons are ordinarily employed and their opposed runs should be driven at equal speed to get the proper feed without wrinkling. This is a difficult matter. If they are not driven at the same speed there results a pleating or ruffling of the work. In the present device the apron merely supports the work from beneath and screw-adjustment causes application of proper pressure to maintain frictional contact between the padding of the lower ironer, the goods and the apron, to move the supporting or delivery apron with the goods. Another objection to the use of an apron for driving, is that it becomes slack. It is made of ordinary canvas. The apron of the present invention is not in contact with any heated element.

Although the screw means for adjusting the ironing instrumentalities have been shown as adapted to simultaneously adjust these elements, and although the carrier apron is shown as movable with the lower ironer means, it will be understood that there is no intention to be limited to the exact construction or the exact manner of adjusting. Although it is desirable to simultaneously move the ironing aprons in opposite directions away from respective ironing faces of the chest yet it is conceivable that means may be provided for the separate and independent adjustment of each ironing element. Although the delivery apron or work carrier is now mounted to move with the frame which carries the lower ironing belt, yet it is conceivable that this feed apron may be mounted for independent adjustment, and so that it will not move in unison with the frame of this lower ironing belt.

The straight line feed provided by the upper runs of the belts 168, the upper surfaces of which are coplanar with the upper surface of the steam chest, is an important feature. The goods is thus fed in one plane. The padded roll 164 has a peripheral speed a little greater than the feed belts 168, and thus the goods is straightened before it reaches the ironing point. This is an important feature and is claimed.

I claim as my invention:

1. A flat work ironer including a steam chest, belt-like padded friction ironing means adapted to iron the goods by moving it across the face of the chest, a second belt-like padded friction ironing means adapted to receive the goods and iron it in the same manner across the opposite face of the chest, a delivery apron adapted to receive the goods from the second ironing means after ironing, means for adjusting the ironing means toward and away from the chest whereby the degree of frictional contact may be varied, and means by which the apron is caused to move toward and away from the chest with the second ironing means during adjustment.

2. A flat work ironer including a steam chest, an ironing apron adapted to iron the goods by

moving it across the face of the chest, a second ironing apron adapted to receive the goods and iron it in the same manner across the opposite face of the chest, and a delivery apron adapted to receive the goods from the second ironing apron, after ironing, and support it, means for supporting the aprons, means for adjusting them, and connections by which the delivery apron is supported for adjustment with or independently 10 of the second ironing apron.

3. A flat work ironer having a steam chest, an ironing apron adapted to iron the goods by moving it across the face of the chest, a second ironing apron adapted to receive the goods and iron it by moving it across the opposite face of the chest, a delivery apron adapted to receive the goods from the second ironing apron and support and move it after ironing, and means adapted to adjust each ironing apron with respect to the working faces of the steam chest.

4. A device of the class described including a flat steam chest, a padding covered belt-like means for moving the goods along one face of the chest and applying pressure thereto, similar 25 pad-covered belt-like means adapted to receive and continue motion of the goods along the opposite face of the chest, the structure of each belt-like means including slat-like elements arranged transversely to the line of movement and upon which the padding is mounted, and means extending in direction of feed and engaging the slats to hold them in flat or coplanar relation in the chest-engaging area.

5. A flat ironer including a steam chest and means for heating it, said steam chest having opposingly arranged plane faces, a belt-like padded apron having one run engageable with one face of the chest in a manner to feed and iron the goods, a second belt-like padded apron having its upper run arranged to engage the opposite face of the steam chest and adapted to receive the goods and iron and continue motion thereof along the bottom face of the chest and a third belt-like carrier arranged below said second apron adapted to receive the goods and feed it to a point outside of the machine and means adapted to bodily move the belt-like padded aprons toward and away from the chest, and to move the carrier toward and away from one of 50 the aprons.

6. A flat ironer including a steam chest and means for heating it, said steam chest having opposite faces, a belt-like padded apron having one run engageable with one face of the chest in a manner to feed and iron the goods, a second belt-like padded apron having its upper run arranged to engage the opposite face of the steam chest and adapted to receive the goods and continue motion thereof along the bottom face of the chest and iron it, a belt-like carrier arranged below said second apron and adapted to receive the goods and feed it to a point outside of the machine, means for adjusting the aprons, and means whereby said carrier is moved with the second apron when the latter is adjusted.

7. A device of the class described including a steam chest, padded belt means for moving the goods along one face of the chest, additional padded belt means adapted to receive and continue motion of the goods along the opposite face of the chest, and means for bodily moving both padded belt means toward and away from the steam chest.

8. A device of the class described including a 75 steam chest, an ironing apron having padding

thereon adapted to feed goods across one face of the chest, a second ironing apron having padding thereon and adapted to receive and continue feeding of the goods across another face of the chest, a carrier adapted to receive the goods from the last mentioned apron after ironing, the said carrier being mounted to move with the second apron, and means for simultaneously adjusting the ironing apron and carrier toward and away from said steam chest, and additional 10 means for adjusting the carrier toward and away from said second apron independently of the ironing means.

9. In a laundry machine, a fixed steam chest having a flat pressing surface, endless pressing means movable during a pressing operation and comprising spaced rigid backing means covered with a padding which padding is cooperative with the goods on the pressing surface for performing an ironing operation, and continuous means acting on the backing means by which every portion of the padding in the ironing zone is maintained in constant pressure ironing relation with the goods on the pressing surface throughout the ironing operation.

10. In a laundry machine, a steam chest having a flat pressing surface, endless pressing means cooperative with the pressing surface for performing an ironing operation, said endless means including link chains cross-connected by slats adapted to form ventilators, padding supported by and engaging the slats and cooperative with the pressing surface, and means cooperating with that portion of the endless pressing means which is opposed to the pressing surface to maintain a strictly coplanar relation of the slats and therefore of the padding throughout the entire pressing area, whereby pressure in the pressing zone is constant throughout the entire area.

11. A device of the class described including a flat surfaced steam chest, pressure ironing means cooperative with the flat surface for an ironing operation and comprising belt-like elements and means for driving them, adjustable means supporting the driving means, slats cross-connecting the belt-like elements, means for holding the slats in coplanar relation to provide a flat surface opposed to the flat surface of the chest, endless padding covering the slats, and means for moving the driving means supporting means and slat-holding means bodily toward and away from the chest to correspondingly move the pressure ironing means to vary the pressure on the goods.

12. A flat work ironer including a steam chest, a first endless ironing means above the chest 55 adapted to iron the goods by moving it across one face of the chest, and comprising sprocket chains and means for driving them, slats cross-connecting the chains, means for causing those slats which are opposed to the working face of the chest to be kept in parallel relation with said face, a second endless ironing means substantially identically similar to the first, and below the chest in opposition to a lower face thereof, and means for synchronizing the movements of the 60 ironing means to cause the goods to be ironed on the upper surface of the chest and be delivered for a similar ironing operation on the bottom surface of the chest, and means below the second ironing means and cooperable therewith to 65 receive the ironed goods and deliver it in flat condition to that end of the chest opposite the end at which the goods was introduced to the first ironing means.

13. A device of the class described including a 75

- steam chest, a padding-covered belt-like means for moving the goods along one face of the chest and applying pressure thereto, the structure of said belt-like means including slat-like elements 5 arranged transversely to the line of movement and upon which the padding is mounted, and means extending transversely to the slat-like elements and effective upon the slat-like elements to hold all of them against motion in a direction 10 away from the chest, in the ironing zone.
14. A device of the class described including a steam chest, endless pressure ironing means cooperative with the steam chest for an ironing operation and adapted to feed the goods during ironing, and including belt-like elements and closely spaced irons cross-connecting the belt-like elements, means acting on the irons in the pressing zone to hold them all against movement away 15 from the goods and working surface of the chest,

endless padding covering the irons and means for supporting said endless means, and means for adjusting said supporting means toward and away from the chest to vary the ironing pressure and to cool the padding on the goods.

15. In an ironing machine, a heated ironing surface, an endless pressing means having spaced rigid backing means cooperable with said surface for performing a feeding and ironing operation, and continuous means acting on the backing 10 means for preventing any portion of the endless pressing means in the ironing zone from moving away from the ironing surface and goods thereon, and for causing said pressing means to be pressure-engaged with every portion of the goods 15 on the ironing surface throughout the ironing operation.
